AUTOMATIC STEERING APPARATUS

Lev A. Trofimov, Willoughby, Ohio

Application February 5, 1944, Serial No. 521,217

5 Claims. (Cl. 318—489)

1

This invention relates to automatic pilot systems for controlling the course-direction of a vessel, airplane, or other moving dirigible body.

The invention comprises in general a gyroscope, and a power unit controlled thereby, for moving the course-changing or course-correcting or stabilizing mechanism of the dirigible body.

As a simple illustrative embodiment of the invention I have chosen to describe it herein as applied to the control of a vessel or airplane rudder, for steering the vessel in two dimensional space; and it is believed that it will then be apparent to those skilled in the art how to apply the invention to the control of the stabilization, direction, and attitude of an airplane, dirigible balloon, or the like in three dimension space; even if more than one such system as that described herein may be needed to effect complete control.

Automatic pilot systems of the class referred to have been proposed, comprising a gyroscope, and a power unit controlled thereby to change the position of the rudder, to hold the vessel on its course, responsive to movements of the vessel or its tendency to move from the course; but in all such prior systems of which I have knowledge, there is unavoidably introduced a time interval or delay between the movement of the vessel from its course and the correcting movement of the rudder.

This in some cases is caused by the necessary inclusion in the system of intermediate agencies or operating apparatus between the gyroscope and the power unit, which require time for their operation; and in other cases is caused by a delay in the response of the power unit itself.

The vessel therefore will have deviated from its course to a great degree before any correcting or course-restoring effect of the system comes into action; and the vessel will swing or yaw from side to side of the course through a wide angle, proportional to the amount of said time interval or delay.

When the dirigible body is of great weight and inertia, the power unit to operate the rudder will accordingly be of great horsepower; and to effect its actuation by the gyroscope the actuating power developed by the gyroscope must in general be amplified; and in prior systems this amplifying apparatus has also introduced delay between the actuating movement of the gyroscope and the movement of the rudder.

According to the present invention, this delay has been eliminated or reduced to a negligible minimum. In the specific embodiment of the

2

invention herein disclosed the power unit derives its power from a motor, preferably but not necessarily an electric motor, which at all times runs at full speed or at a high-power speed. A power transmission of the toothed gearing type is provided between the motor and a rotary output shaft operatively connected at all times to the rudder. Some torque is at all times developed by the transmission and applied to the output shaft in opposing directions even while the output shaft is at rest, so that the teeth of the gearing are always loaded and all lost motion in the transmission is eliminated. To cause the output shaft to move in either direction of rotation from rest, or to change the speed or direction of rotation, or to bring it again to rest, all that is necessary is to change the relative degree of energization of a pair of electromagnetic windings. These windings are at all times energized. Their

20 energization is balanced or unbalanced as the case may be, by a rheostat or potentiometer operated directly by the gyroscope. The rheostat may be of very small size and respond very sensitively to the gyroscope.

25 The rudder accordingly begins to move in one correcting direction or the other instantaneously, upon the initiation of any movement of the vessel from its course, and restores the vessel to its course, and concurrently restores the rudder to its normal course position. Furthermore, means is provided by which the rudder will be held in a moved position if extraneous influences continue to act on the vessel tending to cause it to leave the course.

30 Again, the more rapidly the vessel tends to move from its course, the more rapidly will the rudder be moved in the corresponding direction and the farther it will be so moved.

35 Thus any movement or tendency to movement of the vessel from its course is counteracted instantaneously by a corresponding corrective movement of the rudder.

It is accordingly among the objects of the invention:

40 45 To provide generally an improved automatic pilot system of the class referred to;

To provide an automatic pilot system of the class referred to, in which the objections to prior systems referred to above are eliminated;

50 To provide an improved automatic pilot system having the advantages and operative characteristics and mode of operation mentioned above;

To provide an automatic pilot system of the 55 class referred to in which the rudder or other

steering or stabilizing mechanism of a dirigible vessel, airplane, or the like, may be moved by the power of a motor, including motors of great horsepower, by changing the relative amounts of energization of a pair of stationary electromagnetic windings which are at all times energized, by the movements of the movable element of a potentiometer or rheostat having mechanical connection with a gyroscope.

Other objects will be apparent to those skilled in the art to which my invention appertains.

My invention is fully disclosed in the following description taken in connection with the accompanying drawing, in which:

Fig. 1 is a diagrammatic view illustrating a system embodying my invention as applied to the rudder of a vessel;

Fig. 2 is a fragmentary view similar to a part of Fig. 1 illustrating a modification which in some cases may be used;

Fig. 3 is a diagrammatic view illustrating another embodiment of my invention applicable to cases in which the power to operate the rudder must be of great horsepower.

Referring to the drawing, Fig. 1, I have indicated diagrammatically at 1 the rudder of a vessel, at 2 the motor supplying power to move the rudder, and at 3 a gyroscope.

The gyroscope 3 is illustrated diagrammatically as being of well known construction, and will be understood without further illustration or description; it being believed sufficient to say here that it has a rotary element driven by a source of power not shown, and has a shaft 4; and that when the vessel upon which it is mounted is moving along a preselected course, the shaft 4 remains at rest, relative to the vessel and apparatus thereon; but that upon deviation of the vessel from its course in one direction or the other, the shaft 4 will remain rotatively stationary in space; but, relative to the vessel, will be rotated correspondingly in one direction or the other, and upon return of the vessel toward its course will rotate relatively in the opposite direction.

The motor 2 is illustrated diagrammatically as a direct current shunt motor, and runs continuously, tending to run at a constant speed, so long as the apparatus is in operation. As will be apparent hereinafter, this motor may be any other type or kind of motor, for example an internal combustion motor. Since this motor is not started and stopped in the application of its power to the rudder, but runs continuously, it may run at its most efficient speed and therefore may be of smaller size and with smaller rated horsepower than would otherwise be possible.

Illustrated generally at 5 is a double differential gearing driven by the motor 2. It comprises two spider elements 6 and 7 provided with gear teeth at their outer peripheries meshed together as at 8, and rotated in opposite directions by a gear 9 on the shaft 10 of the motor 2.

There may be any suitable speed ratio between the motor 2 and the spiders 6 and 7, the drawing having been simplified by showing simply one gear 9 between them.

The spider 6 rotatably supports pinions 11 and 12 meshed with differential gears 13 and 14; and the spider element 7 rotatably supports pinions 15 and 16 meshed with differential gears 17 and 18.

Connected to the differential gears 13 and 17 are pinions 19 and 20 both meshed with a single gear 21 which latter gear is connected to an out-

put shaft 22 upon the end of which is a clutch element 23. The output shaft 22 may be considered as in two axially aligned parts 22 and 24 which, in the operation of the system, are clutched together by the clutch element 23 and by a clutch element 25 splined for axial movement on the output shaft portion 24.

A cable drum 26 on the output shaft portion 24 has a cable 27 wound thereon and passing over pulleys 28 and 29 and connected at its ends to opposite arms 30 and 31 on an oscillatably supported rudder post 32 connected to the rudder 1.

In a manner to be more fully described, the motor 2 supplies power through the transmission 5 to the output shaft 22-24 in one direction or the other to move the rudder 1 in one direction or the other; but if it be desired to operate the rudder 1 independently of the automatic pilot mechanism, a change-over to that mode of operation

may be effected as follows. A lever 33 pivotally supported at 34 is rotated on its pivot and its inner end, engaged in a clutch shifting groove 35 associated with the clutch element 25, withdraws the clutch element 25 from engagement with the clutch element 23, and the same movement meshes a gear 36 associated with the clutch element 25 with a gear 37 on a shaft 38 to which power is supplied by hand or by motor; the source of such power not being shown, to simplify the drawing, inasmuch as those skilled in the art will know how to apply such power to the shaft 38.

Connected to the differential gears 14 and 18 are control shafts G1 and G2 upon which are mounted the rotary elements of electric generators 39 and 40, which in the preferred type are direct current generators having series field windings 41 and 42 and shunt field windings 43 and 44.

As stated, the spider elements 6 and 7 in this embodiment are rotated in opposite directions and therefore tend to rotate the pinions 19 and 20 in opposite directions, and when the torques of the pinions 19 and 20 are equal, the pinions 19 and 20 and their differential gears 13 and 17 tend to remain at rest, and the differential gears 14 and 18 and their shafts G1 and G2 tend to rotate in opposite directions at twice the speed of the spider elements 6 and 7.

The output terminals of the generators 39 and 50 40, driven by the shafts G1 and G2, are connected in series with each other by a circuit comprising a wire 45 connecting the generators to each other, wires 46 and 47 connecting the generators to their respective series field 41 and 42, and a wire 48 connecting the series fields. The generators are poled to oppose each other, potentially.

The shunt field 43 of the generator 39 is connected across that generator, one side of the field winding being connected to the wire 46 and the other side being connected through a flexible connector 49 to one end of a resistor 50, thence through a part of the resistance of the resistor to a movable rheostat arm 51, and thence by a flexible connector 52 to the wire 45; and the field winding 44 is similarly connected across its generator 40, at one end to the wire 47 and at its other end by means of a flexible connector 53 to the other end of the resistor 50 and back to the other side of the generator 40 by way of the arm 51 and the flexible connector 52.

With the rheostat arm 51 in an intermediate position on the resistor 50, the shunt field windings 43 and 44 will be energized across their respective generators 39 and 40 to a condition of

balance at which the potentials of the generators 39 and 40 will be equal and opposite in the series circuit described above.

Each generator will then generate current in its own local shunt field circuit as described above. This puts a small load or braking action on the shafts G1 and G2 and causes a small torque or load to be developed at the pinions 19 and 20, acting oppositely on the gear 21, and thereby all lost motion or back-lash is removed from all of the teeth of the interengaged gear teeth of the system.

When the rheostat arm 51 is in the position referred to at which the energization of the two shunt field windings 43 and 44 is balanced, that is, are energized respectively to the degree at which the two generators develop equal load torques, the system is in normal balanced condition, and the output shaft 22-24 remains at rest and the rudder 1 consequently remains at rest.

This condition obtains when the vessel is proceeding on its course, and the shaft 4 of the gyroscope 3 is relatively at rest. The shaft 4 is connected to the rheostat arm 51 as shown.

If now due to any cause the vessel should deviate or begin to deviate from its course, in one direction or the other, the gyroscope shaft 4 will begin to turn, relatively, in one direction or the other, and move the rheostat arm 51 in the corresponding direction, to cut resistance into the circuit of one shunt field winding 43 or 44, and cut it out of the other; thereby causing one generator 39 or 40 to have a potential overpowering that of the other, and causing current to flow in the series circuit comprising: the generators, the series field windings 41 and 42 and the wires 45, 46, 47, and 48 as described.

The generator whose potential is thus made greater than that of the other continues to act as a generator and the current generated by it and flowing from it in the series circuit and through the other, causes the other, to act as a motor. The generator unit which acts as a generator develops electrical load in the series circuit, which draws more torque from the differential gearing and causes the generator to slow down.

It is a characteristic of this differential gearing as illustrated and described, that no matter at what relative speed the shafts G1 and G2 rotate, the arithmetical sum of their speeds is a constant. If therefore one of the shafts G1 or G2 slows down as just described, the other shaft will be speeded up by the gear interconnections. By causing the generator unit which is not acting as a generator to motorize, it will be caused to tend to run at a higher speed, by electrical power supplied to it from the one which is running as a generator. By design, as will be understood by those skilled in the art, the speed at which the motorizing unit tends to run, may be caused to be at all times greater than the speed at which it tends to be driven by the gearing. It follows that the electrical load developed by the unit which is running as a generator, and which acts as a braking load on the gearing, is not lost, but is conserved and converted by the motorizing unit into mechanical power and put back into the differential gearing system.

By giving the two units 39 and 40 both series and shunt windings, when one unit begins to act as a generator, the electrical load which it develops is rapidly built up or magnified, producing a rapidly magnified braking load on its shaft G1 or G2, and this, as will now be clear, causes one

shaft G1 or G2 to slow down rapidly and run slower than the other.

Upon thus putting braking torque on one shaft G1 or G2 and speeding up the other shaft, the torques at the pinions 19 and 20 will no longer be equal and opposite, but will act on the gear 21 in the same direction and turn it together with the output shaft 21-24, and move the rudder 1.

As a specific illustrative example, if the rheostat arm 51 be moved counter-clockwise, the generator 40, acting as a generator, will develop more electrical load and torque and put an increased braking action on the shaft G2, which will slow down that shaft and the differential gear 18. This will cause the pinion 20 to increase in speed and to have increased torque applied on it, because the torques on the shaft G2 and pinion 20 are at all times equal. This, in the absence of any other agency, would cause the gear 21 to turn and to drive the pinion 19 and cause the shaft G1 to increase in speed; but this is supplemented by the overdriving motor action of the unit 39, which also tends to cause the shaft G1 to increase still farther in speed, and causes the pinion 19 to apply torque to the gear 21 to help drive it.

As the end result, there is a position for the rheostat arm 51 at which the system is balanced, and the gear 21 and output shaft remain at rest; and upon moving the arm 51 by the gyroscope to unbalance the system, the gear 21 and output shaft are turned, and all of the power put into the system by the motor 2 is delivered to the gear 21 to turn it, the turning of the gear 21 resulting from putting a braking load on one of the shafts G1 or G2; and this braking load is converted back into mechanical power and fed back into the gearing system and applied to the gear 21.

Inasmuch as the motor 2 is constantly running, and the generators 39 and 40 are constantly driven and the field windings 43-44 are constantly energized, the slightest change in the position of the rheostat arm 51 due to the initiation of deviation of the vessel from its course will cause movement of the rudder 1 in the course-correcting direction. The movement of the rudder 1 in the course-correcting direction will therefore be concurrent with movement of the rheostat arm 51 without the interposition of any time interval therebetween.

When the deviation of the vessel from the course has been slowed down and finally stopped, by movement of the rudder, it is desirable to have the rudder stop moving in the course-correcting direction. To accomplish this the rheostat arm should then be on the balancing point of the resistor. If the vessel then begins to turn back toward the course, it is desirable to have the rudder reverse and move back toward the normal central position; and to accomplish this the rheostat arm should be on the other side of balancing point. And as the vessel approaches the course direction the rudder should move far enough to prevent the vessel from swinging beyond the course-direction and to stop its return movement when in the course-direction.

This is accomplished by the following means taken in connection with the fact that the gyroscope shaft stops rotating and reverses when the vessel stops deviating and begins to return.

Upon the output shaft 22 is a cable drum 54 upon which is wound a cable 55 extending in opposite directions from the drum, and running over pulleys 56-56; and the ends of the cable are secured respectively to arms 58-58 connected to 75 a resistor support 59 upon which the resistor 50

is mounted, the support 50 and arms 58 being mounted to rotate in unison about the axis of the shaft 4, the diagrammatic drawing showing them mounted to rotate on the shaft as a bearing support. The connection points of the cable ends to the arms 58 is adjustable to change the effective radial length of the arms 58.

With this arrangement when the arm 51 moves, say, counter-clockwise to find unbalancing positions on the resistor 50, and the rudder 1 moves correspondingly in the correcting clockwise direction, rotation of the shaft 22 which moves the rudder will rotate the drum 54, and by means of the cable 55 will move the resistor support 59 also counter-clockwise, and carry the resistor 50 under the arm 51 so that the balancing point on the resistor moves toward the arm 51.

In general as the vessel begins to deviate, the movement of the rheostat arm will at first exceed that of the movement of the rudder and resistor support, but this causes the rudder to accelerate and causes the movement of the resistor support to accelerate and overtake the rheostat arm; and this is contributed to by the fact that as the rudder moves it slows down the rate of deviation and correspondingly slows down the relative movement of the gyroscope shaft 4, and of the rheostat arm.

The vessel now returns toward the course, and as it does so the rheostat arm is moved to the other side of the balancing position by reversal of the gyroscope shaft 4; and the rudder reverses. Again, the arm gains on the rudder until the latter speeds up and causes the resistor support to overtake the arm, which causes the rudder return to slow down. As the rudder returns it causes the vessel to return more and more slowly so that the rheostat arm moves more slowly. The rudder and rheostat arm reach their course position at about the same time, but if there should be any overtravel of the vessel from the course it will be corrected by another similar cycle of lesser dimensions.

In Fig. 2 is shown a modification in which the series field windings 41 and 42 have been omitted, the shunt windings 43-44 alone supplying energization to the generators, the generators being connected in series by the wire 45, and in this case by a wire 48a corresponding to the wire 48 of Fig. 1.

The operation using this modification will be substantially the same as that of the form of Fig. 1 except that when one of the generators begins to generate and drive the other as a motor the electrical load does not build up to as great a value. In other words the system with the modification of Fig. 2 is not quite as sensitive in response as that of the form of Fig. 1, but may in some cases be sufficiently sensitive.

In Fig. 3 is illustrated another form of the invention which may be used when the dirigible body is of great weight and inertia and great horsepower is needed to operate its rudder.

In this connection, it may be stated, as explaining the purpose for the form of Fig. 3, that the form of Fig. 1 could be increased in horsepower size to any extent to adapt it to a dirigible body such as a sea going vessel of great size and inertia, by providing a sufficiently large rudder 1, and a sufficiently powerful motor 2, and increasing the size of the differential gearing and the generator units 39 and 40; but this would call for a large rheostat 50-51 and a correspondingly large gyroscope 3. In some cases, however, it would be more desirable to employ a small horse-

power system of the kind illustrated in Fig. 1 utilizing a small gyroscope, etc., and utilizing the output shaft 22, not to operate the rudder directly, but to actuate a large horsepower system supplying power to the rudder. Such an arrangement is shown in Fig. 3.

The parts in the upper left hand corner of this figure including the gear 9 and the output shaft 22 are the same as in Fig. 1. The power-supplying motor for this part of this system, however, as shown at 2A, is an alternating current induction motor supplied with current from three phase mains 66-60.

The motor for the rudder is shown at 61 and is also an alternating current motor of the squirrel cage induction type arranged to be driven continuously from the mains 60. The rudder in this figure is not shown but at 32A is a rudder post from which connection to the rudder is made.

At 5A is a differential gearing and generator-motor arrangement which in its essential parts has been shown as identical with that of Fig. 1, the parts corresponding to those of Fig. 1 having the same reference characters with the suffix A, by which expedient it is believed that a complete description thereof is unnecessary because it will be understood from the description of the corresponding parts of Fig. 1.

Differences and other additional parts, however, will now be described.

The output shaft 22A drives a worm 62 meshed with a worm gear 63 on the rudder post 32A.

In this form the resistor 50A is stationary, that is to say, is not mounted upon a movable resistor support as in Fig. 1. A rheostat arm 51A moves over the resistor 50A by being mounted upon a rotatable shaft 64, and the opposite ends of the resistor 50A are connected by wires 65 and 66 respectively to the field windings 43A and 44A, and the arm 51A is connected by a wire 67 to the wire 45A.

With the motor 61 rotating, upon movement of the arm 51A in one direction or the other over the resistor 50A the output shaft 22A and consequently the rudder post 32A will be rotated in one direction or the other or brought to rest as will now be clear.

To thus move the rheostat arm 51A in response to movements of the gyroscope shaft 4, the following means is provided.

At 68 and 69 respectively are a transmitter and a receiver of the Selsyn type comprising three phase stators 70 and 71 respectively and single phase rotors 72 and 73 respectively, the stators being interconnected by a three phase system 74 and the rotors being energized across the common single phase alternating current mains 75 which are energized from one of the phases of the three phase mains 66-60.

The rotor 72 is connected to the shaft 22. The rotor 73 is connected to a shaft 76 at one end, the other end of the shaft being connected to the spider element 77 of a differential gearing shown generally at 78 and comprising pinions 79-79 rotatably supported by the spider element 77 and differential gears 80 and 81 meshed with the pinions. The differential gear 80 is to be driven concurrently with the shaft 22A and to this end is connected to a spur gear 82 which is driven by rotary movement of the pinion 19A. For convenience this driving connection may be made through an idler gear 83, and at any suitable gear ratio.

The differential gear 81 is connected to the aforesaid shaft 64.

In the operation of the form of Fig. 3, the gyroscope 3, responsive to deviation of the vessel from the course, will actuate the differential gearing 5 and turn its output shaft 22 as described for the form of Fig. 1. This will unbalance the Selsyn units 38 and 40 and cause rotation of the shaft 16. Rotation of the shaft 16 will turn the spider 17 and cause the pinions 18-18 to react upon the differential gear 30, which at this time is stationary and turn the differential gear 31 and the shaft 34 to move the rheostat arm 31A away from its balancing position on the resistor 30A to one side or the other thereof.

This will unbalance the energization of the field windings 43A and 44A of the generators 39A and 40A and cause power of the motor 61 to turn the gear 21A and thereby the worm 62 and worm gear 63 and the rudder post 32A.

Rotation of the gear 21A, accompanied of course by rotation of the pinion 18A, is transmitted to the gear 62 and rotates the differential gear 30 in the direction to reduce or stop rotation of the shaft 34, and movement of the arm 31A, and to ultimately return the arm again to its balancing position.

It is believed that from this brief description of the form of Fig. 3, its operation will be clear; and that it will be apparent that the differential gearing 18 controls the relative positions of the rudder post 32A and rheostat arm 31A as does the cable drum 54, cable 55, and resistor support 59 of the form of Fig. 1. The rudder on the rudder post 32A therefore will be moved to correct for deviations of the vessel from its course in the same way as the rudder 1 was moved in the form of Fig. 1.

In practice and for purposes of economy of manufacture, it will be preferable for the units 39 and 40 to be identical, with identical field windings, and for the two parts of the double differential gearing to be alike; and similarly for the units 39A and 40A and the differential gearings and the field windings of the units of Fig. 3. In such case, for the balanced condition described herein-before at which the output shaft 22 or 22A remains at rest, the two field windings would be equally energized. However, the invention may be practiced equally well if the two generator units or their respective field windings are not exactly alike and if the ratios of the gears in the differential gearing is such that the two units do not run at equal speeds, so that in the balanced condition at which the load shaft remains at rest, the fields may be unequally energized.

In order to avoid complications of description and complications in the claims, and to adequately cover the invention by claims, it is believed proper here to use the word "balanced" as describing the relative degrees of energization of the two respective fields which causes the output shaft to remain at rest, and "unbalanced" as describing them when they cause the output shaft to rotate; and these words or their derivatives have been used with this definition in claims.

I claim:

1. An automatic pilot system for dirigible vessels and the like, comprising: a movable element for controlling the direction of the vessel; a continuously running power-supplying motor; a transmission for transmitting motor power to the element; the transmission comprising differential gearing constantly driven by the motor; a pair of rotary electro-dynamic devices constantly driven by transmission-transmitted motor power; a rotary output shaft connected to the element;

a pair of continuously energized electromagnetic devices, and a rheostat controlling the degree to which the electromagnetic devices are relatively energized to cause them to be balanced and unbalanced; a gyroscope compass and means associated therewith for causing operation of the rheostat to unbalance the energization of the electromagnetic devices upon deviation of the vessel from its course, and to operate the rheostat toward balancing the devices upon return of the vessel toward its course; the electrodynamic devices being responsive to unbalanced energization of the electromagnetic devices to cause the transmission to deliver power to the output shaft to rotate it and move the element; movable means moved by power delivered by the transmission and associated with the rheostat to operate it to tend to restore balanced energization of the electromagnetic devices; and the electrodynamic devices being responsive to balanced energization of the electromagnetic devices to cause the transmission to discontinue the delivery of power to the output shaft.

2. The system described in claim 1 and in which the electrodynamic devices have the construction of electric generators and the electromagnetic devices are in the form of field windings for the generators and the generators are driven by the differential gearing; and generate equal electrical loads and develop equal braking loads on the gearing when the energization of their fields is balanced, and develop an increasing braking load on one generator and differential gearing, when the fields are progressively unbalanced.

3. The system described in claim 1 and in which the electrodynamic devices have the construction of electric generators and the electromagnetic devices are in the form of field windings for the generators; and the generators are driven by the differential gearing and generate equal opposing potentials and equal electrical loads when the energization of their fields is balanced; and, when their fields are unbalanced, one is driven as a generator, and drives the other as a motor.

4. An automatic pilot system for dirigible vessels and the like, comprising: a movable controlling element for controlling the direction of the vessel; a continuously running power-supplying motor; a transmission for transmitting motor power to the controlling element; the transmission comprising a rotary output element connected to the controlling element; control means for the transmission comprising a pair of constantly energized electromagnetic windings; the transmission being responsive to deliver power and rotate the output element in one direction or the other or to bring it to rest, as the energization of the windings is relatively unbalanced or balanced respectively; means to control energization of the windings comprising a rheostat, and a gyroscope connected to it to operate it to tend to effect unbalanced energization of the windings upon deviation of the vessel from its course, and to tend to effect balanced energization of the windings upon return of the vessel toward the course; and means operable by power delivered by the transmission, to operate a rheostat to cause it to tend to restore balance of the windings.

5. An automatic pilot system for dirigible vessels and the like, comprising: a movable element for controlling the direction of the vessel; a continuously running power-supplying motor; a transmission for transmitting motor power to the element; the transmission comprising differ-

tial gearing constantly driven by the motor; a pair of rotary torque developing devices constantly driven by transmission-transmitted motor power; a rotary output shaft connected to the element; torque controlling means controlling the relative torques developed by the devices to cause them to be balanced and unbalanced; a gyroscope compass and means associated therewith for causing operation of the torque controlling means to unbalance the torques upon deviation of the vessel from its course, and to balance them upon return of the vessel toward its course; the transmission being responsive to unbalanced torques to deliver power to the output shaft to rotate it and move the element; movable means moved by power delivered by the transmission and associated with the torque controlling means to operate it to tend to restore the torques to

balance; and the transmission being responsive to balanced torques to cause the transmission to discontinue the delivery of power to the output shaft.
